LATCH MECHANISM

Ray N. Du Shane, Jr., Fullerton, Calif., assignor to
Northrop Architectural Systems, Los Angeles, Calif., a
corporation of California

Filed Dec. 3, 1962, Ser. No. 241,688
22 Claims. (Cl. 70—97)

The present invention relates to a latch mechanism and more particularly to a non-jamming latch mechanism movable into three positions and adapted to be used on doors and panels.

The latch mechanism of the present invention is primarily used on sliding doors or panels but it is understood that other types of doors may be used. Today, it is common to manufacture sliding doors and door frames from extruded metal frame members. These frame members such as stiles and jambs, may vary in size, shape and section depending on the design and function of the door or panel.

The present latch mechanism is universal in that it is adapted to be used with substantially all types of frame members (stiles and jambs) regardless of shape and size, with sliding as well as other types of doors or panels, and with locking devices of different constructions and sizes.

Moreover, the present latch mechanism is adapted to assume three positions: latching, unlatching and non-jamming. The latter position prevents the mechanism and door or panel from being damaged when inadvertently the mechanism is in the latched position and the door or panel is closed.

In addition, the latch mechanism of the present invention prevents the door or panel from being lifted upwardly from the threshold or bottom door frame member (sill) when an attempted forcible entry is made on a home or dwelling having the said latch mechanism. It has been found that homes have been illegally entered by prying and urging sliding doors or panels slightly upwardly into space in a head member to remove a door from sliding contact with a sill member. The entire length of the bottom rail of the door or panel is generally required to be lifted above the sill member in order to remove the door or panel. Doors or panels provided with the present latch mechanism are not capable of being removed by this method.

The present invention also includes novel structure of a latch keeper means used to latchingly engage a latch or strike member and which moves in a vertical plane, and a latch keeper actuating means which moves in a second vertical plane substantially normal to the first vertical plane. This allows the latch keeper actuating means to be actuated from a side face of a door or panel stile and the latch keeper means to operate in a plane parallel to the end face of a door or panel. A latch actuating button may be movably carried within a recessed portion of the door frame, jamb or panel stile to enable sliding doors equipped with the present latch mechanism to be moved closely adjacent each other in opposite face to face position without interference of protruding elements.

Anti-jimmying means is also included in the present latch mechanism to prevent the latch keeper from being pried open or jimmied when latched.

In general, the latch mechanism of the present invention includes an elongated, horizontally extending latch strike member rigidly carried on a jamb or frame member of a sliding door or panel, an opening in the vertical edge wall of the frame member of a second door or panel for receiving the latch strike member, and means carried by the second door or panel for latch-

2

ing and unlatching the latch member when received through the opening. This latching means may comprise a latch keeper which is spring biased against the inner face of the edge wall of the frame member of the second door or panel, a latch keeper actuating means for moving the latch keeper into and out of latching position with the latch member, and a novel connecting means for transmitting movement between the latch keeper actuating means and latch keeper means when the two latter means are adapted to be moved in vertical planes substantially normal to each other. Moreover the connecting means allows the latch keeper means to be moved into a non-jamming position to prevent damage to the mechanism when the latch keeper means has been inadvertently moved into a latched position, the door or panel is closed and the latch member is received in the opening and strikes the latch keeper means.

An object of the present invention is to provide a novel latch mechanism for use with sliding doors or panels.

Another object is to provide a latch mechanism which is universal and may be used with all types of doors or panels irrespective of size and shape of the frame members, stiles or jambs.

Another object is to provide a latch mechanism which is burglarproof.

A further object is to provide a latch mechanism for sliding doors or panels which cannot be jimmied or pried open.

Still another object is to provide a latch mechanism which is adapted to assume three positions, latching, unlatching and non-jamming.

Another object is to provide a latch mechanism including a latch keeper means and latch keeper actuating means which move in vertical planes substantially normal to each other and connecting means for transmitting sliding movement between the two means in different vertical planes.

A specific object of the invention is to provide an interconnecting means between a reciprocally movable latch keeper member and actuating means therefor whereby motion imparted to the actuating means is readily transmitted to the latch keeper member such interconnecting means permitting the latch keeper member to be moved into non-jamming position. In one exemplary embodiment of the invention, such interconnecting means includes a transverse plate-like member readily assembled and mounted for pivotal movement with respect to actuating means. In another exemplary embodiment, a transverse pin carried by the latch keeper member is guided by slots receiving opposite pin ends and the latch keeper member is pivotal about the pin axis into non-jamming relation with the latch strike member.

The present invention contemplates a novel construction of a latch mechanism which may be used in door panels having vertical stile members of relatively narrow width and with limited exceptionally small space for receiving a latch mechanism, and wherein the vertical parallel lines of the stile members outlining the panel frame and glass therein may appear virtually unbroken by door hardware, such as latch housings, hardware or door pulls. The present latch mechanism embodies an arrangement of a latch keeper means, latch keeper actuating means, and an interconnecting means which permits loose tolerances and ready adaptability to locks of different manufacture, and size, and operation.

Other objects and advantages of this invention will be readily apparent from the following description when considered in connection with the appended drawings.

In the drawings:

FIG. 1 is a side elevation of a pair of sliding doors

latched together by an exemplary latch mechanism of the present invention.

FIG. 2 is a transverse section of the device taken along plane II—II of FIG. 1.

FIG. 3 is a side elevation of a sliding door latched to a jamb member of a door frame by an exemplary latch mechanism of the present invention.

FIG. 4 is an enlarged longitudinal section through the latch mechanism of FIG. 3 taken generally in the area designated by the circular phantom line IV and illustrating the latch mechanism in the unlatched position.

FIG. 5 is a longitudinal section of the device taken along plane V—V of FIG. 4.

FIG. 6 is a transverse section of the device taken along plane VI—VI of FIG. 4.

FIG. 7 is a longitudinal section of the device taken through the latch mechanism of FIG. 3 and is similar to FIG. 4 except the latch mechanism is in the non-jamming position.

FIG. 8 is a perspective view of an exemplary latch mechanism of the present invention and illustrates the mechanism in the latched position.

FIG. 9 is a fragmentary sectional view of a different embodiment of this invention, the sectional view being taken in a vertical plane bisecting the latch mechanism and associated frame members.

FIG. 10 is a fragmentary sectional view taken in the same plane as FIG. 9 and illustrating the latch mechanism in latched position.

FIG. 11 is a fragmentary sectional view taken in the same plane as FIG. 9 showing the latch mechanism in non-jamming position.

FIG. 12 is a fragmentary transverse enlarged sectional view taken in the plane indicated by line XII—XII of FIG. 9.

In describing the present invention, the term "frame member" may include a jamb or other elements of a door frame or movable panel frame, or the stile, upper rail or other structural framing elements normally used in making and assembling a door or panel construction for an opening. Moreover, it should be understood that the present latch mechanism may be used to latch a door or panel to a jamb (FIG. 3) or to another door or panel (FIG. 4) and is especially adapted for use on sliding doors or panels and such an example will be so described.

An exemplary latch mechanism 10 of the present invention may be provided on two adjacent frame members adapted to be latched together. As seen in FIGS. 3 to 8, a frame member 11 may be a jamb forming part of a door frame and the other frame member 12 may be a stile of a sliding door. The frame member 12 may have a vertical edge wall or face 13 and spaced vertical side walls or faces 14a and 14b adapted to enclose the major portion of the latch mechanism 10 of the present invention.

The jamb or frame member 11 may rigidly carry an elongated, horizontally extending latch strike member 15 which may be a bolt having an enlarged headed end 15a. The latch member 15 may be adjustably secured to the frame member 11 by any well known means, such as by interior nut 16 and exterior stop nut 17 which may be adjusted on the threaded portion of the bolt 15 to control and vary the horizontal distance between the enlarged end portion 15a and the frame member 11.

The frame member or stile 12 is provided with an opening 21 in the vertical end face 13 thereof for receiving the latch strike member 15. A movable latch keeper means 22 may be provided within stile 12 for latching and unlatching the latch member 15 when received in the opening 21.

Latch keeper means 22 may be slidably carried within a latch keeper housing 23 and movable in a vertical plane substantially parallel to the vertical end face 13 of the frame member 12. The housing 23 is substantially elongated and channel-shaped in section and the wall 24

of the housing 23 is rigidly secured to the end face 13 of the frame member 12 by means of screws 24a and 24b. The side walls of the housing 23 are indicated at 25a and 25b and act as guides for the vertical movement 5 of the latch keeper 22. An opening 21a is provided in the wall 24 of housing 23 and is in horizontal alignment with opening 21 for receiving latch member 15 within frame 12.

The latch keeper means 22 is preferably elongated and 10 has a width slightly less than the distance between the side walls 25a and 25b of housing 23. This allows the keeper means 22 to slide within the housing 23 but transverse movement is prevented. The upper end 22a of keeper means 22 adjacent the wall 13 of frame member 15 15 may be convex for facilitating pivotal movement of the latch keeper 22 into a non-jamming position as shown in FIG. 7 and as described hereinafter. The lower end 22b of latch keeper means 22 may include a furcated or forked locking end portion adapted to engage the enlarged 20 headed end 15a and prevent the latch member 15 from withdrawal from openings 21 and 21a.

Spring means 27 may be provided for biasing the latch keeper means 22 toward the vertical end face 13 of the frame member 12 and for tending to maintain movement 25 of the latch keeper means 22 in its vertical plane. Spring means 27 extends vertically and is elongated and curved in longitudinal section. Its upper end has a transverse retaining strip 27a whose ends are received in vertical slots 28a and 28b in side walls 25a and 25b respectively. 30 Screw 24a may extend against or through a port in strip 27a to secure the spring means 27. This allows the spring 27 to be held at its upper end leaving its lower end 27b free to move rearwardly as described hereinafter and still maintain biasing pressure on the latch keeper 22.

35 A latch keeper actuating means is provided for moving the latch keeper means 22 between a latching position (FIG. 8) in latching engagement with the latch member 15 when received through the opening 21 and an unlatching position (FIG. 4) out of latching engagement with the latch member 15. Such an actuating means is indicated as 30 and may be slidably carried on wall 14a of frame member or stile 12 and movable in a second vertical plane which is substantially normal to the first vertical plane in which the latch keeper 22 moves. Actuating means 30 is provided with a vertically extending slot 31 slidably receiving a horizontal pin 32 which is rigidly carried by the side wall 14a of the frame member 12. The vertical stroke or travel of means 30 and latch keeper 22 is determined by the length of slot 31 and 40 diameter of pin 32. An upper reduced hook-like end 30a of actuating means 30 extends through a vertical slot 35 in side wall 14a. A latching button member 33 movably carried on the exterior side of the side wall 14a is suitably connected to hook-like end 30a. The exterior 45 face of side wall 14a may include a hardware plate 14c providing a recessed portion 34 for receiving latching button 33 and to prevent the latching button member from protruding transversely beyond the plane defined by the exterior face of side wall 14a and to therefore allow 50 close sliding relation with other sliding doors or frame members. Any suitable means may be utilized in rigidly connecting the upper end 30a of actuating means 30 and the latching button 33.

The lower end 30b of means 30 may have two downwardly extending spaced legs 36 and 37 adapted to straddle a cylinder type lock means 50 during vertical movement of the actuating means 30. Each leg 36 and 37 may be provided with an outwardly directed dovetail-shaped slot 38 whose function will be described in detail 55 hereinafter.

A connecting means is provided for transmitting vertical sliding movement of actuating means 30 to latch keeper means 22, said means 30 and 22 being movable in vertical planes substantially normal to each other. Such connecting means also allows the locking portion 22b of

latch keeper means 22 to move rearwardly and away from the edge wall 13 of the frame member 12 and into a non-jamming position (FIG. 7) and against the bias of the spring means 27 when the latch member 15 moves through the opening 21 and strikes the latch keeper means 22.

An exemplary connecting means may include a horizontal, transversely extending plate member 39 which is rigidly carried by the latch keeper means 22 by a pair of horizontally extending spaced finger members 40a and 40b. The free transverse edge 39b of plate member 39 may be slidably and frictionally received in dovetail-shaped slot 38 in the leg 36 of actuating means 30. The cooperation between the entrance of the dovetail-shaped slot 38 and the transverse edge 39b of plate member 39 is such that vertical sliding motion is transmitted by actuating means 30 to latch keeper 22 and the free transverse edge 39b of plate member 39 is still adapted to be rocked about a transverse axis and moved in a vertical direction within the dovetail-shaped slot 38 when the latch keeper means 22 is forced into a non-jamming position as shown in FIG. 7.

The other transverse edge 39a of the plate member 39 forms a horizontal shoulder portion 39c between fingers 40a and 40b, portion 39c being in continuous sliding frictional engagement with the spring means 27. As best seen in FIGS. 4 and 8, the horizontal shoulder portion 39c is adapted to be positioned on opposite sides of the convexly curved section of spring means 27 when the latch keeper means 22 is moved between unlatching and latching positions, respectively. The cooperation of the portion 39c and the curved spring means 27 provides an anti-jimmying means for preventing jimmying and accidental movement of latch keeper means 22 when an attempt is made to move keeper means 22 from latched to unlatched positions. As can best be seen in FIG. 8, if a sharp instrument was inserted into opening 21 in an attempt to move the latch keeper means 22 upwardly, the curved portion of the spring 27 would act as a stop for shoulder portion 39c and latch keeper 22.

It is understood that when the latch keeper actuating means 30 is moved between latching and unlatching positions, the horizontal shoulder portion 39c actually tends to flatten the curved spring 27 during movement of the members between the two positions. After the horizontal portion 39c has moved over the curved portion of the spring 27, it is very difficult for the latch keeper means 22 to be accidentally moved in a vertical direction by any other means than the latch actuating means 30.

A particular advantage of the present invention is the lack of close tolerances that are needed in certain critical portions of the mechanism, which eliminates high cost of production. For example, the actuating means 30 is adapted to cooperate with any portion of the transverse, edge 39b of plate member 39 and slight transverse movement therebetween does not cause the mechanism to become inoperative.

The latch keeper means 22 may be inadvertently or accidentally moved into a latching position when the horizontal latching member 15 is not within the opening 21, as when the sliding door is in open position. When frame member 12 is then moved toward frame member 11, the latching member 15 will strike the locking portion of latch keeper means 22. In many latching mechanisms used heretofore, damage would be caused to the latching mechanism, to the frame members, or to both. This is not possible with the latching mechanism of the present invention.

As can best be seen in FIG. 7, the frame members 11 and 12 are not latched and the latch keeper means 22 is in the latching position. When the frame members 11 and 12 are moved together, the latch member 15 will move through the opening 21 and strike the latch keeper means 22. This causes the latch keeper means 22 to move rearwardly against the bias of the lower end 27b

of the spring 27 and into the non-jamming position as shown in FIG. 7. The latch keeper 22 during this movement rocks or pivots at the point of engagement between the free transverse edge 39b of the plate member 39 and the edges of the dovetail-shaped slot 38 in the actuating means 30. Since the actuating means 30 is stationary due to the pin 32 engaging the upper end of the slot 31, rearward movement of the lower end of the latch keeper 22 causes the upper end of the latch keeper 22 to be rotated or rocked so that the free transverse edge 39b of the plate 39 moves upwardly into contact with the upper slanted edge of the dovetail-shaped slot 38. This rocking movement is permitted by the convex upper end 22a of the latch keeper 22 as it slidably engages the front wall 23 of the latch keeper housing 24.

A separate lock means 50 may be carried on the side wall 14b of and within the frame member 12 for locking the latch keeper means 22 into latching and unlatching positions. The separate lock means 50 may include rotatable upper and lower locking fingers 51a and 51b which are adapted to be rotated into selected contact with the plate member 39. The lock means 50 may be a suitable cylinder type of lock which is actuated by a key. Such a lock is well known and therefore will not be described in detail. As shown by the phantom lines in FIG. 7, the locking fingers 51a and 51b can be rotated to engage plate member 39 for moving and locking the latch keeper means 22 into latching and unlatching positions. It should be noted that even when the upper locking finger 51a has been rotated downwardly into contact with plate 39, and the latch keeper 22 is in latching position, the latch keeper 22 can still be moved rearwardly into the non-jamming position when struck by the latching member 15. Moreover, no strain or damage can be transmitted to the lock member when the keeper 22 moves into the non-jamming position because plate member 39 tends to move away from locking finger 51a. This eliminates any possible damage to the aligned tumblers in a cylinder type lock.

The present invention also provides means for preventing burglars from attempting to actuate the latch mechanism and from forcing the door open. The jamb or frame member 11 may be provided with a vertical, channel-shaped in section, elongated portion 42 for receiving the frame member 12 and for enclosing that space between the frame members 11 and 12 where the latch member 15 extends through the opening 21 when the frame members 11 and 12 are latched together. It is seen in FIG. 6 that the channel-shaped member 42 may be the extruded section of frame member 11 or may be an extruded part rigidly carried by the frame member 11 and extends over adjacent faces of the side walls 14a and 14b of the frame member 12 a sufficient distance to prevent a tool or other means from being inserted between the two frame members and reaching the latch member 15. FIG. 2, discloses an elongated, channel-shaped member 42a which serves the same function as the member 42 in FIG. 6, but is provided on the frame member or stile of a sliding door which is adapted to be latched to another sliding door as seen in FIG. 1.

Homes have also been burglarized by having the doors lifted upwardly above the sill member. When the lower end of the door is above the sill member, the lower portion of the door is pulled outwardly thus allowing entry into the home. This is not possible with the latching mechanism of the present invention. As best seen in FIG. 7, if the door carrying the frame member 12 is lifted upwardly, the lower wall of opening 21 in frame member 12 would strike the latching member 15 which is stationary. This would prevent raising of the door a sufficient distance so that it could be disassembled from the threshold member.

The operation of the latch mechanism of the present invention is very simple and is as follows: the two frame members 11 and 12 are brought together so that the

latching member 15 is received within the opening 21 as shown in FIG. 4. The latching button 33 is moved downwardly thus actuating the means 30. The downward movement of actuating means 30 is transmitted to the latch keeper means 22 by the cooperation of the dovetail-shaped slot 38 and plate 39. The latch keeper means 22 is thus moved downwardly in a vertical plane substantially normal to the vertical plane in which the actuating means 30 is moved. The furcated locking end 22b of latch keeper 22 is moved downwardly to straddle the latching member 15 behind the headed end 15a into the position shown in FIG. 8. The frame members 11 and 12 are thus prevented from being moved apart and are therefore latched together by the enlarged end 15a on the latching member 15 and the furcated end 22b of the latch keeper means 22.

During movement of the latch keeper means 22 from the unlatched position to the latched position, it is understood that the horizontal shoulder portion 39c of plate member 39 is in continuous sliding contact with the spring means 27. During such movement, the spring 27 is urged towards a flattened condition until the horizontal shoulder portion 39c is moved over the curved portion of the spring 27. Due to the cooperation of the curved spring 27 and the horizontal shoulder portion 39c, it is very difficult if not impossible for the latch to be jimmied or pried open.

In order to unlatch the frame members 11 and 12, the latching button 33 is moved upwardly causing the actuating means 30 to slide relative to pin 32 and move the latch keeper means 22 upwardly into an unlatched position as shown in FIG. 4. The latching member 15 is thus free to retract horizontally through the opening 21.

As explained hereinabove, even if the latch keeper means 22 has been inadvertently moved into a latching position when the frame members 11 and 12 are separated, no damage will result when the frame members 11 and 12 are moved together so that the latching member 15 strikes the latch keeper means 22. In this event, the latch keeper means 22 will move rearwardly against the bias of spring 27 into the position shown in FIG. 7.

In the embodiment of this invention shown in FIGS. 9-12, inclusive, similar reference numerals have been applied to parts similar to those in the previous embodiment except that the present reference numerals are in the 100 series. In this exemplary embodiment, a jamb member 111 is shown in opposed adjacent relation to a stile 112 on a movable or sliding panel. Projecting from jamb member 111 is a latch strike bolt or member 115 provided with an enlarged headed end 115a. Latch member 115 may be adjustably mounted on jamb member 111 by well-known means such as interior and exterior nuts 116 and 117, such adjustment positioning headed end 115a in selected relation with latch keeper member 122 when the door panel is in closed, locked position (FIG. 10).

Stile 112 includes an edge wall 113, side walls 114a and 114b, and a suitable inner configured edge wall portion 113a adapted to cooperate with a glass pane. Edge wall 113 has an opening 121 aligned with and of a size to permit passage therethrough of headed end 115a. Similarly, the wall 124 of the latch keeper housing 123 is provided with an opening 121a for bolt 115.

Latch keeper housing 123 may be secured to edge wall 113 by top and bottom screws 124a, 124b and may include side walls 125a and 125b in parallel relation and serving to guide vertical reciprocal movement of latch keeper member 122 therebetween. Top inwardly extending portions 160 on side walls 125a, 125b may be ported at 161a and 161b, respectively, to rotatably mount a stub shaft 162 which extends through a port 163 in side wall 114b of stile 112. Shaft 162 is carried by handle 164 which may be moved about the pivotal axis of shaft 162 for actuation of the latch mechanism as hereafter described.

The latch keeper means 122 may include a bottom bifurcated locking portion 122b adapted to straddle the shank of bolt 115 behind headed end 115a in down-locking position. The upper end 122a of latch keeper means 5 122 comprises spaced inwardly extending lug portions 140a and 140b, the outwardly and upwardly directed edges of said lug portions being convexly curved to permit said latch keeper means 122 to be moved into angular relation with respect to edge wall 113 when in non-jamming position.

10 Latch keeper means 122 is normally maintained in parallel sliding relation with the inner surface of housing wall 124 by a spring member 127 having at top end 127a secured to housing 123 by reception thereof in slots 128a and 128b and by screw 124a as in the prior embodiment. The bottom end of spring member 127 includes a convexly curved portion 127b normally biased against the opposed inner face of latch keeper means 122.

Means interconnecting latch keeper means 122 and 20 latch keeper actuating means generally indicated at 130 (which includes handle 164, stub shaft 162) may comprise a horizontal transverse pin member 139 carried in aligned ports 165a and 165b in portions 140a and 140b, respectively. Pin member 139 projects beyond said portions 25 140a and 140b and opposite ends of pin member 139 extend into aligned parallel vertically disposed slots 166a, 166b in top portions 160 of the latch keeper housing 123. The cooperable engagement of the pin ends and slots provides vertical guiding of the top end of latch keeper means 122 when it is actuated between latching and unlatching position.

Between lug portions 140a and 140b the pin member 139 is received within and between forked leg portions 168 defining a transversely extending slot 169 having sufficient depth so that the pin member will not contact the bottom of the slot 169 during movement of the latch keeper means between latching and unlatching position. The forked leg portions 168 are provided on an arm 151 which extends from a ported hub member 150 which is fixedly 40 carried by shaft 162 between portions 160 of the latch keeper housing 123. Arm 151 may be provided with a radially inwardly extending bore 170 for partially enclosing and seating a coil spring 171 having an outer end seated against the pin 139 at 172. Spring 171 serves as 45 a detent-type locking anti-jimmying spring for positively retaining the latch keeper member in selected latched or unlatched position and serves the same function as the convex portion of spring 27 of the prior embodiment.

In actuation of the latch means, movement of handle 50 164 upwardly from the position shown in FIG. 9 (and after the jamb and stile are in closed relation) will cause arm 151 to move downwardly, pin member 139 to move downwardly in slots 166a and 166b, and the latch keeper means 122 will be moved downwardly in parallel sliding 55 relation to wall 124 of the latch keeper housing 123. As handle 164 passes a horizontal line through the axis of shaft 162, locking spring 171 will be compressed in bore 170. As the forked end portion of arm 151 begins to be directed downwardly, spring 171 will expand and exert a 60 spring force against pin member 139 to further facilitate downward movement of the latch keeper means 122 into latching engagement with the latch bolt or member 115. Such latching engagement is shown in FIG. 10.

When handle 164 is pressed downwardly to unlatch 65 the latch mechanism, latch keeper means 122 is urged upwardly by arm 151 and engagement of the lower leg 168 with pin member 139. Spring 171 is again compressed as the handle passes a horizontal line and as the forked end of arm 151 begins to be directed upwardly, spring 70 171 exerts a spring force assisting in the movement of the handle 164 and latch keeper means 122 into upper unlatched position. Engagement of pin member 139 with the ends of slots 166a and 166b limits downward or upward movement of the latch keeper means 122. It will be 75 apparent that spring 171 serves to retain the latch keeper

move rearwardly and away from the edge wall of said second frame member into a non-jamming position and against the bias of said spring means when said latch keeper means is in the latched position and when said latch member moves through said opening and strikes said latch keeper means, whereby the latch mechanism is non-jamming and is adapted to be moved into latching, unlatching and non-jamming positions.

10. A latch mechanism as stated in claim 9, wherein said connecting means includes a horizontal, transversely extending member carried by said latch keeper means; and slot means on said latch keeper actuating means receiving said horizontal member.

11. A latch mechanism as stated in claim 9, including anti-jimmying means operatively connected with said latch keeper means for preventing jimmying and accidental movement of said latch keeper means when moved respectively into latching and unlatching positions.

12. A latch mechanism as stated in claim 11, wherein said spring means extends vertically and is elongated and has a longitudinal curved section, and said anti-jimmying means includes a horizontal shoulder member rigidly carried by said latch keeper means and in sliding frictional engagement with said spring means, said horizontal shoulder member being adapted to be positioned on opposite sides of said curved section when said latch keeper means is moved between latching and unlatching positions.

13. A latch mechanism as stated in claim 9, wherein said elongated latch member has an enlarged end and said latch keeper means includes a furcated end portion adapted to engage said enlarged end and prevent said elongated latch member from being withdrawn from said opening.

14. A latch mechanism as stated in claim 9, wherein said first frame member is provided with a vertical, elongated, channel-shaped in section, burglar-proof means for receiving said second frame member where said latch member extends through said opening when the frame members are latched together.

15. In a latch mechanism for use with a sliding door having a frame member adapted to be latched to a frame member on another door or jamb, the provision of: a frame member having an edge face and spaced side faces, latch keeper means slidably carried within and by said frame member and movable in a plane substantially parallel to said edge face for latching and unlatching cooperation with a latch member adapted to be received through an opening in the edge face of said frame member, latch keeper actuating means for moving said latch keeper means between a latching position and an unlatching position, said latch keeper actuating means being slidably carried within and by said frame member and being movable in a second plane which is substantially normal to said first plane, and connecting means for transmitting sliding movement of said actuating means to said keeper means, both of which are movable in planes substantially normal to each other, said keeper means having a connection with said actuating means whereby said keeper means is movable rearwardly and away from the edge face of said frame member into a non-jamming position when said latch keeper means is in the latched position and is struck by a latch member moving through the opening in the edge face of said frame member.

16. In a latch mechanism for use with a sliding door having a frame member adapted to be latched to a frame member on another door or jamb, the provision of: a frame member having an edge face and spaced side faces, latch keeper means slidably carried within and by said frame member for latching and unlatching a latch member adapted to be received through an opening in the edge face of said frame member, latch keeper actuating means within and movably carried by said frame member for moving said latch keeper means between latching and unlatching positions, and means having a connection with said actuating means and having a connection with said

keeper means for moving said keeper means, at least one of said connections including a pivotal connection whereby said latch keeper means is movable rearwardly and away from the edge face of said frame member into a non-jamming position when said latch keeper means is in the latch position and is struck by a latch member moving through the opening in the edge face of said frame member.

17. In a sliding door latch mechanism for locking opposed members of a door assembly, at least one of which is movable toward and away from the other member, the combination of: a headed latch bolt projecting from one of said members; the other of said members having a latch bolt receiving opening aligned with said bolt; latch keeper means movable on said other member and having a locking portion cooperable with the latch bolt; means mounting said latch keeper means on said other member for movement transverse to the axis of the latch bolt for latching and unlatching engagement therewith and for movement of the locking portion of the latch keeper means away from the latch bolt for non-jamming engagement with the latch bolt; and actuating means for said latch keeper means including a transverse member having a connection with said latch keeper means and including movable means on said other member in engagement with said transverse member for transmitting movement of the movable means to said latch keeper means for actuation thereof into and out of latching engagement with said bolt.

18. A latch mechanism as stated in claim 17, wherein said mounting means for said latch keeper means includes parallel aligned slots provided on said other member for guiding reception of said transverse member during transmission of movement of said movable means.

19. A latch mechanism as stated in claim 17, wherein said transverse member is a pin, said other member is provided with slots receiving ends of said pin and guiding the same during movement of the latch keeper means to latching and unlatching positions, said latch keeper means being rotatable about the axis of the pin when the latch keeper means is moved into non-jamming position by said latch bolt.

20. In a sliding door latch mechanism for locking opposed members of a door assembly, at least one of which is movable toward and away from the other member, the combination of: a latch bolt means on one of said members; bolt engagement means on the other of said members movable longitudinally thereof for latching and unlatching the bolt means and movable away from said bolt means into non-jamming position of the engagement means; movable actuating means on the other member for the bolt engagement means; and means interconnecting the actuating means and the bolt engagement means for translating movement of the actuating means into longitudinal movement of the bolt engagement means, said interconnecting means including a pivotal connection for movement of the bolt engagement means about an axis thereof into said non-jamming position.

21. A latch mechanism as stated in claim 20 including spring means between said actuating means and said interconnecting means for spring biasing said bolt engagement means into latching position and into unlatched position.

22. In a sliding door latch mechanism for locking opposed members of a door assembly, at least one of which is movable toward and away from the other member, the combination of: a headed latch bolt projecting from one of said members towards the other of said members; said other member being hollow and having a latch bolt receiving opening for reception of said headed bolt into said other member; a reciprocally movable bolt engagement means supported within said other member and movable into latching and unlatching relation with said headed bolt; a transverse member carried at the upper end of said bolt engagement means; actuating means pivotally mounted on said other member and including an

means 122 in its selected position and under a biasing force.

In the event latch keeper means 122 is in latching or down position when the stile is moved into close adjacent relation with the jamb 111 and headed end 115a extends through aligned openings 121 and 121a and buts locking portion 122b, it will be apparent from FIG. 11 that latch keeper means 122 may readily pivot about the axis of pin member 139 so that the locking portion 122b may silently yield upon contact with headed end 115a to cushion the closing action and to prevent shock and damage to the latch mechanism and the door parts. It will be apparent that such yielding is made under increasing spring pressure from spring member 127, such spring member being subject to bending at 174 about a convex edge of leg 168 of the arm 151. When the stile 112 is moved away from bolt head 115a, spring 127 returns the locking portion to its normal operative position against wall 124 of the housing 123. Thus, the embodiment shown in FIGS. 9-12 operates in similar manner to the prior embodiment, includes common features of structure and operation, and embodies a structure readily adaptable for modified stile installations.

It is thus seen that the latch mechanism of the present invention can move into three positions: latching, unlatching and non-jamming. This latch mechanism is burglarproof and cannot be jimmied or pried open. It should also be noted that since dovetail openings 38 are provided on either side of the actuating means 30, the latch mechanism of the present invention could be mounted on a lefthand or righthand door without redesigning the mechanism. It is thus seen that a latch mechanism of the present invention is universal and can be utilized on any type of door, stile, jamb or any other type of frame member.

The latch mechanism 10 of the present invention is compact and can be completely enclosed within the standard sizes now being employed for extrusions commonly used for frame members in the present door constructions. As best seen in FIGS. 1 and 3, the latch mechanism 10 will not protrude into the window area of sliding doors and hinder vision therethrough.

Obviously many modifications and variations of the present invention are possible in the light of the above teachings. It is therefore to be understood that within the scope of the appended claims the invention may be practiced otherwise than as specifically described.

I claim:

1. A universal latch mechanism for use with a sliding door having a frame member adapted to be latched to a frame member on another door or jamb comprising: an elongated, horizontally extending latch strike member rigidly carried by a frame member, an opening in a vertical edge face on the other frame member for receiving said elongated, horizontal latch member, latch keeper means slidably carried by said other frame member and movable in a vertical plane substantially parallel to said vertical edge face for latching and unlatching said latch member when received in said opening, spring means for biasing said latch keeper means towards the vertical edge face of said other frame member and for tending to maintain movement of said latch keeper means in said vertical plane, latch keeper actuating means for moving said latch keeper means between a latching position in latching engagement with said latch member when received in said opening and substantially covering said opening, and an unlatching position out of latching engagement with said latch member and substantially uncovering said opening, said latch keeper actuating means being movable in a second vertical plane which is substantially normal to said first vertical plane, and connecting means between said latch keeper means and latch keeper actuating means for transmitting vertical sliding movement therebetween and including movement of the latch keeper means rearwardly and away from the edge face of said other frame

member into a non-jamming position and against the bias of said spring means when said latch keeper means is in the latched position and when said latch member moves through said opening and strikes said latch keeper means, whereby the latch mechanism is non-jamming and is adapted to be moved into latching, unlatching, and non-jamming positions.

2. A latch mechanism as stated in claim 1, including separate lock means carried on the side of said other frame member for locking said latch keeper means in latching position, said latch keeper means being still adapted to be moved into the non-jamming position.

3. A latch mechanism as stated in claim 1, wherein said connecting means includes a horizontal, transversely extending plate member rigidly carried by said latch keeper means and a dovetail-shaped slot provided in said latch keeper actuating means, said dovetail-shaped slot slidably and frictionally receiving a free transverse edge portion of said horizontal plate member.

4. A latch mechanism as stated in claim 1, wherein said latch keeper means has a convex upper end surface adjacent the vertical edge face of said other frame member for facilitating movement of said latch keeper into the non-jamming position.

5. A latch mechanism as stated in claim 1, including anti-jimmying means operatively connected with said latch keeper means for preventing jimmying and accidental movement of said latch keeper means when moved into latching and unlatching positions respectively.

6. A latch mechanism as stated in claim 5, wherein said spring means extends vertically, is elongated and includes a curved longitudinal section, and said anti-jimmying means includes a horizontal shoulder member rigidly carried by said latch keeper means and in continuous sliding frictional engagement with said spring means, said horizontal shoulder member being adapted to be positioned on opposite sides of said curved section when said latch keeper means is moved into latching and unlatching positions.

7. A latch mechanism as stated in claim 1, including a recessed portion on the exterior side of said other frame member, a latching button member movably carried on said exterior side of said other frame member and within said recessed portion, and means for connecting said latching button member with said latch keeper actuating member.

8. A latch mechanism as stated in claim 1, wherein said elongated latch strike member has an enlarged end and said latch keeper means includes a furcated end portion adapted to engage said enlarged end and prevent said elongated latch member from being withdrawn from said opening.

9. A universal latch mechanism for use with a sliding door having a frame member adapted to be latched to a frame member on another door or jamb comprising: an elongated, horizontally extending latch member rigidly carried by a first frame member, a second frame member having a vertical edge wall and spaced vertical side walls and adapted to be latched to said first frame member, said vertical edge wall on said second frame member having an opening for receiving said latch member, latch keeper means movably carried within and by said second frame member for latching and unlatching engagement with said latch member when received through said opening, spring means for biasing said latch keeper means towards the vertical edge wall of said second frame member, latch keeper actuating means within and movably carried by said second frame member for moving said latch keeper means between a latching position in latching engagement with said latch member when received through said opening, and an unlatching position out of latching engagement with said latch member, and connecting means for transmitting movement of said latch keeper means to said latch keeper means, said connecting means including means for said latch keeper means to

actuating portion provided with a slot receiving said transverse member for pivotal movement of said bolt engagement means about an axis of said transverse member for movement of said bolt engagement means away from said latch bolt into non-jamming relation with said latch bolt; and spring means connected at one end to said other member adjacent to the proximate end of said bolt engagement means, said spring means having its opposite end bearing against said bolt engagement means adjacent the distal end thereof.
